UNITED STATES PATENT OFFICE.

WILLIAM W. HECK, OF STEELTON, PENNSYLVANIA.

RAILWAY-RAIL.

1,278,922.

Specification of Letters Patent. Patented Sept. 17, 1918.

Application filed April 1, 1915. Serial No. 18,567.

To all whom it may concern:

Be it known that I, WILLIAM W. HECK, a citizen of the United States, residing at Steelton, in the county of Dauphin and State 5 of Pennsylvania, have invented certain new and useful Improvements in Railway-Rails, of which the following is a specification, reference being had therein to the accompanying drawing.

- 10 This invention relates broadly to railway rails and more specifically to rails of the sectional type in which a tread-component is removably supported in a base-component.
- 15 The primary object of the invention is to provide a railway rail in which a tread-component is supported in a base-component in such manner that "low joints" are practically precluded whereby an absolutely 20 smooth and substantially unbroken tread-surface is presented.

Another object of the invention is to provide a rail structure which (in the event of the breaking of one of the components thereof,) 25 in its entirety, will remain intact and thereby preclude danger of accidents or wrecks of any kind, a feature which inures particularly to the benefit and safety of the public.

Another object of the invention is to provide, in such a construction, a tread-component 30 so disposed therein that it may readily be removed at any time for replacement, etc., without disturbing the base-components in which it is supported.

35 Still another object of the invention is to provide a railway rail in which is included a series of abutting base-components that constitute practically a permanent structure, and in which are to be supported a series of 40 tread-components so formed and constructed as to be interchangeable and capable of being turned end for end, if desired.

A still further object of the invention is 45 to provide a railway rail, of the character specified, which is readily rolled in the mill into the required shape, economically and readily, and on which it is unnecessary to do any machine work except the punching of bolt-holes.

50 A further object of the invention is to form the base-component of a sectional rail, of the kind specified, with outspreading flanges having their upper surfaces substantially curved to have a close fit in a correspondingly formed tread-component, the latter having a wedge-shaped tongue adapted

to be disposed and rest in an elongated groove, the walls of which diverge toward the aforementioned flanges; this structure being so formed and aggregated as to present no weak points but, on the contrary, to provide substantial strengthening at the points of greatest strain.

A still further object of the invention is to provide a sectional railway rail, including 65 base and tread-components so aggregated relatively as to cause the base-component to support the tread-component at three points at least and independent of the securing bolts, whereby shearing of the latter is prevented.

The invention seeks in general to provide 70 a rail-structure which is particularly adapted for use on railways where the traffic is heavy or the speed of the trains is high, and 75 which structure, from an operative standpoint, will in practical use possess a high degree of efficiency, rigidity, and durability, and which, structurally considered, will be 80 of great simplicity.

Other objects and advantages are also 85 present in the invention and these will be more or less obvious from the annexed drawings and the following description.

The invention resides broadly in the features of construction, and in the aggregation of the components thereof, all as will be exemplified in the construction herein-after set forth, and the scope of application 90 of which will be indicated in the claim here-to appended.

That the invention may be clearly comprehended, drawings illustrating some of the possible embodiments and utilizations of the same are hereto appended as a part of 95 this disclosure; and in which drawings

Figure 1 is a view in perspective, partly in section, of a railway-rail constructed in accordance with my invention;

Fig. 2 is a similar view of the tread-component detached from the base-component;

Fig. 3 is a similar view of the base-component, by itself;

Fig. 4 is a view in vertical transverse section of the structure; and

Fig. 5 is a view in elevation showing the manner of connecting the rail to a frog or switch; a portion of the rail-component in this instance, being shortened to allow the frog-component to connect to the adjoining component.

Referring to these drawings, the reference-

5 numeral 1 designates, generally, a base-portion which, in this instance, is provided with an elongated groove 2, the walls 3 of which converge downwardly to present a substantially flat bottom 4. The walls 3 terminate in outspreading flanges 5, a substantial portion of the upper surface of each of which is curved, as at 6. These curved surfaces, as best seen in Fig. 4, form arcuate continuations or extensions of the diverging walls and extend to the tips or outer edges of the flanges into approximate alinement with the sides of a head-portion on a component about to be described. It is to be understood that 10 a series of these base-portions 1 are to be arranged in an alined and abutting relation so that the grooves 2 of each two components also aline and are practically continuous.

20 The reference-character 7 designates, generally, the tread-component which, in this instance, is shown as including a head-portion 8 having its under-surfaces 9 rolled to conform to the contour of the upper surface 25 of the flanges 5 of the base-component. The head-portion includes a tread-surface and sides 9 spaced apart in approximate parallelism. The under surfaces of the tread-component are curved, as at 10, and these 30 curved surfaces extend in arcuate arrangement from the sides of the head-portion to a point, 11, where they terminate in diverging sides of a substantially V-shaped tongue 12 formed on the tread-component. The curved 35 portions and wedge-portion of each component are arranged to fit snugly together, each having a bearing in a correspondingly shaped portion of the other. The lower edge 13 of the tongue is substantially square 40 and adapted to rest on the bottom 4 of the groove in the base-component.

Each base-component is, preferably and as shown, provided with eight spaced-apart bolt-holes 14, which, as shown in Figs. 3 and 45 5, are preferably elongated, while each tread-component is provided with an equal number of bolt-holes 15. The number of holes may, of course, be varied. Bolts 16 are disposed in these bolt-holes 14 and 15 and have 50 their nuts 17, or a substantial portion thereof, projecting beyond the plane of the side-surface of the tread-component, whereby such nuts may be tightened conveniently.

It is to be understood that the two abutting 55 ends of each tread-component are to occupy a position intermediate of the ends of the base-component which supports them; from which it follows that the abutting ends of the base-component break joints with the 60 tread components.

The elongated form of the holes 14 in the base-component permits contraction and expansion of the rails.

In Fig. 5, I have disclosed the manner of 65 connecting my improved rail to a frog or

switch-component 18. To this end, the lower portion of the rail is cut away to permit the frog-rail or switch member 18 to be connected with the adjoining component.

On oppositely-disposed outer surfaces of 70 the base-component, and directly beneath the outspreading flanges, there are provided longitudinal grooves or depressions 19, which add to the resiliency of the flanges. These grooves, in conjunction with the curved bearing surfaces of the components, permit a slight bending of the metal at that point and this allows for expansion and contraction of the parts without binding between 75 the head and base flanges.

By reason of the aggroupment of the components and the manner of clamping them together by the bolts, as already described, the objectionable feature of "low joints" is prevented, and this is an important consideration in railroad construction. Moreover, 80 by reason of the feature of removability of the tread-components from their supporting base-components, these tread-components are replaceable, or interchangeable. In fact, 85 they may be turned end for end, if desired.

It is also to be understood that it is a feature of my invention not to undercut or otherwise form any portion of the components in such manner as to weaken them 90 at any point.

It is also a feature of my invention to mount the tread-component in the base-component in such manner that the former will be supported by the latter at three 100 points at least, namely, by the flanges engaging the under surfaces 9 of the head-portion and by the lower edge 13 of the tongue seating on the bottom 4 of the groove in the base-component.

By reason of the fact that the walls 3 of the base-component are not arranged in parallelism, it is not so essential that the tongue shall be formed with an exactness, since the bearing portions—provided by the under-surfaces of the head-portion engaging the upper surfaces of the flanges, and by the lower edge of the tongue engaging the bottom 4 in the groove—will carry the weight of and the strains upon the tread-component. Moreover, this arrangement avoids any tendency of the bolts 16 to carry any 110 of this weight or strain; hence, the danger of shearing of the bolts is rendered practically impossible.

115 From the foregoing, it will be perceived that I have succeeded in devising a rail-structure which is well adapted to achieve the several objects and ends in view. The structure is simple and compact in form, 120 and the components thereof are readily constructed.

As many changes may be made in the above construction and many widely different embodiments of the invention can be 125

made without departing from its spirit, it is intended that all matter contained in the foregoing description and shown in the accompanying drawing shall be interpreted as 5 illustrative and not in any limiting sense.

What I claim is:

A sectional railway rail including in combination a tread component having a head-portion comprising upper and side surfaces, 10 and having an elongated tongue with gradually curved, continuous and unbroken under surfaces extending from the sides of the head-portion and terminating in a substantially V-shaped wedge; a base component 15 provided with a longitudinal groove having walls which diverge and terminate in out-spreading flanges having gradually curved upper surfaces which form continuations

of said diverging walls and adapted to embrace the correspondingly curved portions 20 on the tread component, said curved surfaces extending upwardly from the outer edges of said diverging walls and into approximate alinement with the sides of the tread component; said base component being also provided with longitudinal grooves arranged on oppositely-disposed portions of its outer surfaces, under said flanged extensions; and means for securing the components together. 25

In testimony whereof I affix my signature in presence of two witnesses.

WILLIAM W. HECK.
